MARK H. RYDER, OF WILKINSBURG, PENNSYLVANIA, ASSIGNOR TO WESTINGHOUSE ELECTRIC & MANUFACTURING COMPANY, A CORPORATION OF PENNSYLVANIA.

VACUUM-TUBE STRUCTURE AND METHOD OF ASSEMBLING THE SAME.

Application filed November 7, 1922. Serial No. 599,489.

My invention relates to evacuated electric devices of the three-electrode type and particularly to means for and methods of attaching the filament and the filament spring to the supply connections.

In its broad scope, an object of my invention is to provide means whereby rigid mechanical connections and highly conducting electrical connections may be obtained between the various conducting elements of devices of the class described.

More specifically, an object of my invention is to provide a metallic connection between a filament element and conductors adapted to serve as supporting means and as supply means therefor, whereby decreases are effected in the temperature necessary for successfully welding the several parts mentioned.

Another object of my invention is to provide a method of assembling the several parts of a vacuum-tube structure which effects material economies in the final cost of the finished article.

In the design and manufacture of a vacuum tube adapted to operate upon extremely low filament consumptions, as, for instance, a quarter of a watt or less, it was found necessary to redesign every essential element of the usual high-power-tube structure. This was accomplished, along with other modifications, by employing, as a filament, a platinum strip approximately one-eighth as thick as fine tissue paper and one-hundredth of an inch wide.

The junction of such fragile filaments to the supporting elements by means of welds was, at first, accomplished with great difficulty, inasmuch as the nature of the material was such as to require high temperatures for the welding operation. As a result, the filament tended to burn off during the welding operation or to break at the welded point when slightly jarred.

The above mentioned difficulties have been overcome, in my present invention, by the employment of small pieces of nickel-steel as connecting means, the same being welded at one end to the filament and at the other end to the supporting element.

It has further been found that, when a spring is employed to support one end of the filament, it is desirable to utilize a nickel-steel strip as an intermediate connection be-

tween the spring and its supporting element, as hereinafter explained.

With these and other objects and applications in view, my invention further consists in the details of construction and arrangement hereinafter described and claimed and illustrated in the accompanying drawing, wherein:

Figure 1 is a front elevational view of an evacuated electric device embodying my invention, a portion of the containing wall being broken away;

Figs. 2 and 3 are enlarged front and side elevational detail views, respectively, of the connection shown in Fig. 1 between the filament spring and the supporting rods;

Figs. 4 and 5 are enlarged front and side elevational detail views, respectively, of a preferred form of mounting tip designed for use between the filament and the carrier rod;

Fig. 6 is a side elevational detail view of the filament and supporting elements therefor shown in Fig. 1.

In Fig. 1 is shown a vacuum-tube device 1 embodying a design in which the filament power consumption is less than a quarter of a watt, as compared with power consumptions of from three to five watts in tubes of many of the ordinary types. The vacuum-tube device comprises an enclosing envelope 2 having a re-entrant portion 3 at one end terminating in a supporting press 4.

A linearly extending filament 5 has its two ends welded to substantially flat nickel-steel tips or connectors 6 and 7, respectively. A carrier rod 8, which is embedded in the press 4, has its upper end welded to the lower mounting tip 7. The carrier rod 8, which may be made of nickel-steel, is extended through the press 4 and is provided with a terminal conductor 9 electrically connected thereto and designed to serve as one supply lead for the filament 5.

A filament spring 11, which constitutes the subject matter of a pending application of H. M. Ryder, Serial No. 550,485, filed April 7, 1922, and assigned to the Westinghouse Electric and Manufacturing Company, may be made of such materials as tungsten or molybdenum and comprises a central portion 12 and upper and lower bent-back portions 13 and 14, respectively. The nature of the bends connecting the several bent-back

portions is such as provide a spring connection therebetween. The lower bent-back portion 14 is somewhat shorter than the upper portion 13 and is welded to the mounting tip 6.

A carrier rod 15 of nickel or nickel-steel, which is supported from the press 4, has a strip of nickel-steel 16 welded to the upper end thereof in such manner as to provide a portion of V-shape adapted to receive the upper end portion 13 of the filament spring 11. The connection is made rigid by welding. The carrier rod 15 may be extended through the press 4 and provided with a terminal conductor 17 electrically connected thereto and designed to serve as the remaining supply lead for the filament 5.

A grid member 18 of helical shape is disposed about the filament 5 and is carried by a structure 19 supported in the press 4. The structure 19 may be extended through the press by means of a conductor 21 electrically connected thereto and designed to provide an external circuit terminal for the grid 18.

A cylindrical anode plate member 22 is so disposed as to completely surround the filament element 5 and is supported by carrier rods 23 and 24 extending from the press 4. One of the carrier rods, as 23, may be extended through the press to provide an external circuit connection by means of a conductor 25 having one end electrically connected thereto.

The mounting tip 26 shown in Figs. 4 and 5, is distinguished from that shown in Fig. 1 in the provision of a bent-back tip of V-shape, rather than a flat strip. In this design, the supporting rod 8 is first welded to one of the bent-back portions of the mounting tip and the filament then disposed between said end portions and welded therein. The width of the mounting strips shown in Fig. 1, and the bent-back portions of Figs. 4 and 5 is somewhat greater than that of the filament 5 in order to admit of the formation of a weld wherein the molten material completely surrounds the filament 5.

A desirable method for mounting the filament spring in the vacuum-tube structure is as follows:

Assuming the several carrier rods, the grid 18 and the anode 22 to be in position, the mounting tips 6 and 7 are first welded to the upper and lower ends of the filament 5. The lower free end 14 of the filament spring 11 is then welded to the upper mounting tip 6. The filament is next suspended in the space enclosed by the grid 18, and the upper free end of the filament spring 11 is welded to the upper end of the carrier rod 15. The lower end of the filament 5 is then drawn downwardly until the spring 11 exerts the proper tension on the filament 5, whereupon the lower mounting tip 7 is welded to the carrier rod 8.

In view of the foregoing description, it may be seen that an advantage of my invention is the provision of a very rugged vacuum-tube construction, wherein decreases are effected in the breakage of the filament 70 during transit and wherein decreases are effected in the resistance of the welded connection itself. The latter is of importance in view of the relatively low filament-exciting potentials employed in the tube embodying my invention. Other advantages will readily suggest themselves to those skilled in the art.

While I have described certain forms of my invention and while I have pointed out 80 certain of the most obvious purposes thereof, I do not intend that the language employed in the following claims shall be limited to the precise features described, but I intend that the claims shall be construed to 85 cover all combinations that are fairly included therein when read in connection with the prior art, regardless of the details and the functions mentioned in the description or illustrated in the drawing. 90

I claim as my invention:

1. In combination, a filament, a conductor leading thereto and a connecting piece welded to said filament and said conductor, the portion of said connecting piece fused during said welding surrounding said filament. 95

2. In combination, a filament, a conductor leading thereto and a connecting piece welded to said filament and said conductor, said connecting piece being of greater width than 10 said filament at the junction of the two, whereby during the welding operation the connecting piece will be caused to enclose said filament.

3. In combination, a filament, a support 10 therefor including a spring exerting a tension on said filament and a connecting piece welded at one end to the filament whereby the line of action of said spring is along said connecting piece. 11

4. In an evacuated electric device, a filament, mounting tips comprising an alloy of nickel and steel welded to opposite ends of said filament, a carrier rod welded to the mounting tip at one end at said filament, a 11 filament spring having one end welded to the remaining mounting tip, a second carrier rod and a strip of material comprising an alloy of nickel and steel having one end welded to said second carrier rod and providing a 12 jaw, the other end of said filament spring being disposed therebetween and welded therein.

5. In an evacuated electric device, a member of substantially V-shape comprising an 12 alloy of nickel and steel, a filament having one end disposed between the side portions of said member, and welded therein, a carrier rod welded to said member, a mounting tip welded to the other end of the filament, 13

- a second carrier rod, and a filament spring having opposite ends welded to said second carried rod and to find filament-mounting tip.
6. In an evacuated electric device, a member of substantially V-shape consisting of an alloy of nickel and steel, a filament having one end disposed between the side portions of said member and welded therein, a carrier rod welded to said member a mounting tip welded to the other end of the filament, a filament spring having one end welded to said mounting tip, a second carrier rod and a strip of material comprising an alloy of nickel and steel having one end welded to second carrier rod and providing a jaw, the other end of said filament spring being disposed therebetween and welded therein.
7. The method of assembling the parts of a vacuum-tube structure including a hollow grid positioned therein and carrier rods adjacent to upper and lower ends thereof, said method consisting in securing the supply end of a filament to one end of a filament spring, securing the remaining end of said filament spring to said upper carrier rod, exerting a force on said filament and spring until the proper tension obtains in said filament and then welding the lower end of said filament to said lower carrier rod.
8. The method of assembling the parts of a vacuum tube structure including a hollow grid and upper and lower filament-carrier rods, said method consisting in rigidly securing the upper end of a filament to one end of a filament spring, rigidly securing the remaining end of said filament spring to said upper carrier rod, positioning said filament in the space enclosed by said grid, exerting a force on the lower end of said filament until the proper tension obtains in said filament and then welding said lower filament end to said lower carrier rod.
9. The method of assembling the parts of a vacuum-tube structure including a hollow grid and upper and lower filament-carrier rods, said method consisting in welding a mounting tip to the lower end of a filament, securing the upper end of the filament to the lower end of a filament spring, suspending the filament in the space enclosed by said grid, securing the upper end of the filament spring to said upper carrier rod, and then securing said mounting tip to said lower carrier rod.

In testimony whereof, I have hereunto subscribed my name this 13th day of October, 1922.

MARK H. RYDER.

a second carrier rod, and a filament spring having opposite ends welded to said second carried rod and to find filament-mounting tip.

6. In an evacuated electric device, a member of substantially V-shape consisting of an alloy of nickel and steel, a filament having one end disposed between the side portions of said member and welded therein, a carrier rod welded to said member a mounting tip welded to the other end of the filament, a filament spring having one end welded to said mounting tip, a second carrier rod and a strip of material comprising an alloy of nickel and steel having one end welded to second carrier rod and providing a jaw, the other end of said filament spring being disposed therebetween and welded therein.

7. The method of assembling the parts of a vacuum-tube structure including a hollow grid positioned therein and carrier rods adjacent to upper and lower ends thereof, said method consisting in securing the supply end of a filament to one end of a filament spring, securing the remaining end of said filament spring to said upper carrier rod, exerting a force on said filament and spring until the proper tension obtains in said filament and then welding the lower end of said filament to said lower carrier rod.

8. The method of assembling the parts of a vacuum tube structure including a hollow grid and upper and lower filament-carrier rods, said method consisting in rigidly securing the upper end of a filament to one end of a filament spring, rigidly securing the remaining end of said filament spring to said upper carrier rod, positioning said filament in the space enclosed by said grid, exerting a force on the lower end of said filament until the proper tension obtains in said filament and then welding said lower filament end to said lower carrier rod.

9. The method of assembling the parts of a vacuum-tube structure including a hollow grid and upper and lower filament-carrier rods, said method consisting in welding a mounting tip to the lower end of a filament, securing the upper end of the filament to the lower end of a filament spring, suspending the filament in the space enclosed by said grid, securing the upper end of the filament spring to said upper carrier rod, and then securing said mounting tip to said lower carrier rod.

In testimony whereof, I have hereunto subscribed my name this 13th day of October, 1922.
